Specification of Letters Patent. Patented Jan. 19, 1915.

Application filed January 9, 1912. Serial No. 670,177.

To all whom it may concern:

Be it known that I, HERMAN M. SCHWARTZ, citizen of the United States, residing at Northampton, county of Hampden, State of Massachusetts, have invented a certain new and useful Improvement in Brush-Machines, of which the following is a specification, reference being had therein to the accompanying drawings.

10 My present invention relates to automatic machines for drilling holes in brush backs and setting therein tufts or knots of bristles which are held in place by pieces of metal known as staples or anchors.

15 The machine belongs to the general type of machines known as Gane machines, but the machine embodying my present invention also includes mechanism for automatically positioning the brush backs during the 20 operation of drilling and plugging and for presenting to the drill and plunger new brush backs when the previous ones have been completed.

The machine embodying my present invention is wholly automatic, it only being necessary for the operator to keep the bristle reservoir filled with bristles, the machine supplied with flat wire from which the staples are cut, and to replace the completed 30 brush by an undrilled blank. Heretofore so far as is known to me, machines of this character have been constructed to produce only brushes having an even number of parallel rows of bristles as for instance a four-row 35 brush.

The machine embodying my present invention is especially constructed for use in the manufacture of brushes having an uneven number of rows, said rows not being 40 parallel to each other.

The machine shown in the accompanying drawing is intended for use in the manufacture of a three-row brush, the rows of which converge toward the end or tip of the 45 brush. As will be explained later, the complete cycle of operations of this particular machine includes the drilling and tufting of two three-row brushes of the kind described, the parts coming back to their original or 50 starting position after the completion of the second brush. It will of course be understood that the drilling of one blank and tufting of another is proceeding simultaneously.

The machine naturally divides itself into 55 two halves, one of which contains the drill, staple forming and feeding mechanism, the bristle reservoir, knot selecting mechanism, and the plunger together with the operating parts therefor. This half of the machine is 60 conveniently known as the body of the machine. It is also referred to herein as the front half since this is the part nearest the operator. The back half of the machine is 65 known as the head and is devoted exclusively to the blank positioning mechanism by means of which the blanks are presented to the drill and plunger in proper positions and at the proper time.

While I have usually referred to the piece 70 of metal with which the tuft is fastened into the brush back as a staple, I wish to be understood as including by this term any metallic member for securing a single tuft 75 of bristles whether or not of the solid construction known as an "anchor." I have also referred to the piece of bone or celluloid which is drilled and filled with bristles to form the brush, as the brush blank, although it is often referred to in practice as 80 the handle.

The general mode of operation of the machine may for convenience of understanding the following description of the machine be outlined as follows: The knot picker selects 85 a knot of bristles of the right size from the bristle reservoir and conveys it to the channel in the plunger. At the same time the staple forming mechanism cuts a staple from a metal wire which is fed to the dies 90 at proper times. Then the staple pusher pushes the staple forward until it contacts with the knot of bristles, which it thereupon doubles and pushes forward into the plunger nose. The staple pusher and the plunger 95 advance together with the knot of bristles until the nose of the plunger is about in contact with the brush blank, when the pusher advances further and sets the knot of bristles. Simultaneously with this the drill is 100 caused to advance and drill a hole in a brush back which is also held in the carrier. The drill and plunger then retreat, and during this movement the carrier which is stationary so far as movement toward or away from the body of the machine is concerned, is 105 then moved horizontally and vertically to bring the brush blanks in position to have

the next hole in the undrilled brush blank drilled and the corresponding hole in the drilled brush blank filled. This operation continues until the two blanks are drilled and filled. During all this time while the carrier is at rest, it is rigidly locked in position. The carrier is then unlocked, shifted to bring two more brush blanks in position, and then locked in place again when the 10 operation is repeated.

While I have described in this specification the automatic positioning mechanism for presenting the brush backs to the drill and plunger, and since said mechanism is 15 capable of independent use, I have not claimed it specifically in this application, but have done so in the divisional application filed Nov. 4, 1912, Serial No. 729,303.

The invention will be fully understood 20 from the following description taken in connection with the accompanying drawings, and the novel features will be pointed out and clearly defined in the claims at the close of the specification.

In the drawings, Figure 1 is a side elevation of a machine embodying my invention, the front of the machine being at the right of this view. Fig. 2 is an elevation of the front half of the machine looking toward 30 the right in Fig. 1. In this view the pivots of the cam levers have been shown in section to assist in tracing the movement. Fig. 3 is an elevation of the back half of the machine looking toward the left in Fig. 1.

Fig. 4 is a rear elevation of the machine. Fig. 5 is a top plan view of the portion of the machine shown in Fig. 2. Fig. 6 is a side elevation of the brush holder and related mechanism on a somewhat enlarged 40 scale. Fig. 7 is a front elevation of the parts shown in Fig. 6 and on the same scale. Fig. 8 is a detail of the bristle picker arm. Fig. 9 is a detail of the upper end of the slide operating arm 106 and connected parts. Fig. 10 is a detail of the cushion pins for the plunger slide. Fig. 11 is a view in perspective of the parts which actuate the feed wheel. Fig. 12 is a section on line 12-12 Fig. 5. Fig. 13 is a vertical section of the 50 die and punch, and related parts. Fig. 14 is a view in perspective of the parts shown in Fig. 13. Fig. 15 is a side view of the end of the staple pusher. Fig. 16 is a section of the staple pusher on line 16-16 on Fig. 15. Fig. 17 is a section on line 17-17 Fig. 6, 55 showing the parts locked. Fig. 18 is a diagrammatic view illustrating the path of movement of the drill and tufters relatively to the brush blanks, and corresponding with 60 one cycle of movement of the machine. Fig. 19 is a diagram of the horizontal and vertical cams.

Referring to the drawings, the drill 69 (see Figs. 1, 2 and 5) is held in a chuck 65 70 on the drill spindle 71. Said drill spin-

dle 71 is slideable longitudinally in suitable bearings in the frame of the machine and is caused to rotate by a belt (not shown) on a pulley 72. The rear end of the drill spindle 71 is provided with a collar 73 against 70 which rests a spiral spring 74 which tends to hold the drill spindle 71 away from the brush blank. The drill spindle 71 is pushed forward compressing the spring 74 and coming into contact with the brush blank to 75 drill the hole by means of an adjustable stud 125 on an arm 75 secured to a rock-shaft 76 carried in the bearing 78. The other end of the rock-shaft 76 is provided with an arm 79 secured thereto by a set screw 80. 80 This arm 79 has on its lower end a cam roll 81 which contacts with a cam 82 on the main shaft 35. The adjustable stud 125 on the arm 75 furnishes means for varying the depth of the hole drilled in the brush back 85 and to adjust the drill.

Referring more particularly to Figs. 2 and 5 there is shown at 11 the bristle reservoir or hopper in which the bristles are placed in vertical position, and are crowded forward 90 by a follower 12 operated by chains 13 passing over pulleys 14. The chains 13 are kept taut by weights not shown. The forward end of the bristle reservoir is formed by two inclined planes 15 and 16. The bottom 500 95 of the bristle reservoir is adjustable vertically by means of an adjusting screw 501 working in a lug 502 on the frame of the machine.

The tuft forming mechanism consists of 100 a single member called the knot picker designated 18 in the drawings. This member is seen more clearly in Fig. 8. It consists of a thin needle-like piece of metal having a sharp point. The knot picker is straight 105 on one side and inclined on the other side as shown at 19, in Fig. 8. Immediately behind the inclined portion 19 is located a notch 20 within which the bristles are received. The knot picker 18 is forced into 110 one side of the bristle reservoir 11 and the bristles fill the notch 20, after which it is withdrawn taking the bristles in the notch with it. As the knot picker does not go into the middle of the bristle reservoir, but goes in only on one side, it does not disturb 115 the arrangement of the bristles in the reservoir as much, thereby avoiding many of the troubles to which machines of this type are subject and which are caused in the first place by disturbance of the arrangement of the bristles in the reservoir. The size of 120 the notch in the knot picker determines the size of the knot. If it is desired to change the size of the knot a different knot picker 125 having a notch of the desired size is substituted.

The knot picker 18 reciprocates in two opposite registering grooves 550 and 551 (see Fig. 12) the former of which is formed in 120

the side of the member 503, which is adjustable by means of the screw 504, while the other groove 551 is formed in the adjacent side of a member 552 secured to the 5 frame of the machine. The member 552 is fixed and the member 503 is movable forward for the purpose of adjusting the width of the bristle channel which is left between these two members. This bristle channel 41 10 is of a width about equal to the depth of the notch in the knot picker so that all the bristles in the notch 20 are retained in the notch from the time the picker leaves the reservoir. This arrangement for selecting 15 the knot of bristles and determining its size proves very satisfactory in actual practice on account of its extreme simplicity and the fact that it consists of but a single part.

The knot picker 18 is caused to reciprocate by means of the picker arm 21 (see Fig. 2) pivoted at 22, and the arm 21 is itself moved by a cam follower arm 23 pivoted at 24 and connected to the picker arm 21 at about its middle by an adjustable link. This 25 adjustable link is made in two parts 25 and 26, the part 25 being connected with the picker arm 21 by the pivot 27 while the part 26 is connected to the cam follower arm 23 by the pivot 28 shown in dotted lines in Fig. 30 2. The parts 25 and 26 are secured together by a screw 29 in a slot 30 in the part 25 and the adjustment is conveniently made by means of a thumb screw 31 revolving in the lug 32 on the part 26 and in the lug 33 on 35 the part 25, the hole in the latter lug being screw-threaded. From the foregoing, it will be plain that by turning the thumb screw 31 the position which the notch 20 in the knot picker occupies at the left hand end of 40 its stroke (as seen in Fig. 2) may be adjusted, the purpose of this adjustment being to make sure that the bristle picker will always stop at the right time with its knot of bristles opposite the canal in which the 45 staple pusher moves, so that the entire tuft of bristles will be certain to be carried forward down the canal by the staple pusher. The knot picker is operated by a cam 34 on the main shaft 35, said cam driving a cam 50 follower 36 on the lower end of the cam follower arm 23. This cam is a double or cylindrical cam to give the driven part a positive motion in both directions. The end of the bristle picker 18 which is away from the 55 reservoir is secured to a cross-head 37 by means of a pin 38. The cross-head 37 is slidable in the ways 40. The cross-head 37 is itself provided with two vertical guides 56 between which is located a block 57 secured to the upper end of the picker arm 21 by means of the screw 39. This construction is such that the upper end of the picker arm 21 is free to rise and fall as the cross-head 37 is carried forward.

65 The staples by means of which the tufts

of bristles are secured in the holes in the brush blank consist of small pieces of metal of any well known shape cut from a wire or tape of metal. This wire is shown at 42, and is supported upon a reel (not shown) 70 or in some other suitable manner. The wire is fed forward the proper distance and then remains stationary while the staple is being cut.

The feeding mechanism consists of two 75 jaws 43 and 44. The upper jaw 43 is carried on the end of the jaw arm 45, pivoted at 46 to the frame of the machine, and this jaw arm is caused to swing about the pivot 46 a sufficient amount to advance the wire the 80 required distance. The movement of the jaw arm is produced by a cam 47 acting through the follower arm 48, pivoted at 49 to the frame of the machine, and the link 50 pivoted at 51 to the jaw arm 45. The 85 upper end of the follower arm 48 is slotted as shown at 52 and the position vertically of the left hand end of the link 50 in the said slot 52 is adjustable by means of the nut 53 so that the amount which the wire 42 is fed 90 forward at each swing of the jaws 43 and 44 may be varied.

As the cam 47 is conveniently a plate-cam capable of moving the parts in one direction only, there is provided a spring 60 secured at 61 to the frame of the machine, and at 62 to the jaw arm 45. This spring serves to retract the parts after each advance movement of the wire. The lower jaw 44 is guided in a bent portion 58 of the 100 jaw arm 45 and is held in place in the jaw arm by means of the leaf spring 59. The lower end of the lower jaw is given a spherical shape, as shown at 63, and rests in a corresponding spherical cavity 64 in a 105 bell crank lever 65 which is pivoted at 66 to the frame of the machine. The ball and socket joint 63 permits the lower jaw 44 to swing with the jaw arm 45 and at the same time to be given a slight vertical movement 110 by the bell crank 65 to seize or release the tape. The bell crank is provided at the lower end with a cam follower 67 which is in contact with a cam 68 located on the main shaft 35. The parts are so timed that 115 just before the cam 47 begins to advance the jaws 44 and 43 to feed the wire, the cam 68 will move the lower jaw 44 upward to pinch the wire and said cam 68 will hold the lower jaw 44 in this position during the advance movement of the wire. The wire is released by the jaws at the end of the advance movement.

In the machine embodying my present invention, the staple is itself cut out by the 125 punch, leaving the waste, as distinguished from some forms of staple cutting mechanisms which cut out the waste and leaves the staple, and the cutting of the staple takes place just before the staple is used. By this 130

construction the staple is deposited in the staple pusher channel by the punch itself so that the staple is accurately positioned in the channel. The mechanism for accomplishing this consists of a stationary die 83, (see particularly Figs. 13 and 14), of any suitable construction but preferably made in two parts, and the punch 84 which is movable vertically. The punch 84 is carried on the top of a punch-slide 85 guided by slots 86. The punch-slide 85 is slotted vertically as shown at 88 in Fig. 1, to extend around the stationary die 83, and the top of the slot is closed by a cross-member 89 which is essentially a part of the punch-slide 85. To this cross-member 89, the punch 84 is adjustably secured by means of a screw stud 90 and lock nut 91. By means of this stud 90, the punch 84 may be raised or lowered vertically with reference to the punch slide 85.

The punch slide 85 is given its reciprocating vertical movement by a cam 92 connected to the punch slide by a rock-shaft one arm 25 of which carries the cam roll while another arm 505 is connected with the punch slide. The cam 92 is on the main shaft 35, and as it is a rim cam, a spring 506 is employed to hold the roll against the cam and to lift up 30 the punch slide after each stroke. This spring 506 is secured to a third arm 507 on the rock shaft.

After the knot picker is moved back out of the bristle reservoir to the position shown in Fig. 5, the punch 84 having punched out a staple, the staple is pushed down into a channel 96, see Figs. 1, 13 and 14, in which the pusher 97 slides, and the die holds the staple against the bottom of the pusher slide 40 way until the pusher pushes it out from under the punch. The punch 84 is located in front of the bristle channel 41, so that when the pusher 97 advances it pushes the staple forward in the channel 96 until the 45 staple contacts with the front side of the knot of bristles which are held by the notch 20 in the knot picker 18. A further advance of the pusher 97 doubles the bristles and then carries them forward into the brush 50 blank through the nose 98 of the plunger. The junction of the bristle channel 41 and the slideway through the nose of the plunger is curved as will be plainly seen in Fig. 1 at 100 to facilitate doubling the knot of bristles, and the passage into the nose of the plunger is widened out in the vertical plane as seen at 99. By thus constructing this 55 part of the machine the speed of the machine is increased, as the tuft of bristles is doubled with great rapidity. The pusher 97 is shaped in cross section like an inverted T as seen in Fig. 16 and the two projections 601 and 602 fit into grooves in the walls of the plunger. The 60 portion 603 of the pusher stiffens it so that

it will not bend in inserting the staple in hard material. The end of the pusher is cut away as seen at 604, Fig. 15 so that the pusher may not collide with the punch in case the upward movement of the punch 70 does not begin quite soon enough.

In my present machine the front face of the brush blank in its holder occupies a position in the same vertical plane during the entire time during which it is being drilled 75 or tufted. This being the case, it is necessary for the nose 98 of the plunger to move up to the brush blank and then stand still while the pusher 97 advances still further and inserts the knot of bristles and sets the 80 staple. These relative movements of the plunger and pusher are accomplished in the following manner. The plunger nose 98 is in two pieces formed integral with the top and bottom plates 101 and 102 which together form the plunger slide. Registering grooves in the adjacent faces of the two plates 101 and 102 together form the channel 96 in which the pusher slides, and the two plates 101 and 102 are secured together 85 by the cap 103 on the nose of the plunger and a thumb screw 104, seen in Fig. 5. Both the slide and pusher 97 are moved by the cam 105 (see Fig. 2) through the arm 106 pivoted at its lower end to the base of the 90 machine and carrying a cam roll 107. This arm 106 is cored out, as seen in Figs. 1 and 2 to clear the drill spindle 71, and at its upper end is forked in two planes, so that four prongs 108 are formed. These prongs 108 100 embrace a spool 109 (see also Fig. 9) to which is secured by a pin 110 a rod 111 on the front end of which is carried the pusher 97. The ends of the spool 109 are slotted to slide on ways 112 fastened by screws 113 to 105 the frame of the machine. By this arrangement of the parts, the pusher is accurately guided. The pusher being positively connected with the arm 106 is moved constantly. The plunger slide is also caused to move by the arm 106 the prongs 108 of which contact with a series of cushion pins on the slide, but this movement occurs only at the end of each stroke. The cushion pins are indicated at 114 and 115 in Fig. 5. One of 110 these pins is shown in Fig. 10. It is surrounded by a spring 116 and the pin 114 is 115 slidable in the hole but is prevented from coming out by the thimble 117 which is 120 screwed into the hole in the plunger slide. A collar 118 on the inner end of the pin contacts with the thimble 117 and prevents the pin being pulled out by the spring 116. When the arm 106 has advanced until it 125 contacts with the pins 114, it picks up the plunger slide and moves it forward until a cross-arm 120 fastened to the rear end of the lower member 102 contacts with two adjustable stops 121 secured to the table A of the machine. Said adjustable stops 121 are 130

made in the form of bolts passing through lugs 122 and secured in place by set nuts 123. On the reverse movement of the arm 106 the plugger slide moves back coincidently with the pusher until the cross-arm 120 attached to the plugger slide strikes a stop 126 contained in a lug 127 on the frame of the machine, being moved by the two springs 508 one end of each of which is secured to a post 509 on the frame of the machine. At this point the plugger slide stops and the pusher continues its movement until the prongs 108 contact with the back pair of cushion pins, these being numbered 115. The plugger slide which is composed of the top and bottom plates 101 and 102 has near its forward end a hole 128 in which is located the die 83 and punch 84, which are relatively stationary. This hole permits the sliding movement of the plugger slide without interfering with the die and punch.

The movement of the foregoing parts is as follows: After the staple has been cut by the die and dropped into the channel 96 in which the pusher moves, the forward movement of the arm 106 causes the pusher 97 to push the staple forward until it contacts with the knot of bristles which have previously been brought from the bristle reservoir by the knot picker. The plugger continues to advance and doubles the knot of bristles carrying it forward to a point near the orifice of the plugger nose. About this time the prongs 108 contact with the cushion pins 114 and the entire slide and plugger are carried forward until the plugger nose is about in contact with the face of the brush blank at which time its forward movement is checked by the stops 121. Thereafter the pusher advances still a little further and pushes the knot of bristles and the staple into the hole in the brush block and sets the staple, this further forward movement of the pusher being permitted by the cushion pins 114. The reverse movement is as previously described.

The head or back half of the machine will now be described. As previously stated, in the machine embodying my present invention the face of the brush blanks to be drilled and tufted remains in the same vertical plane throughout the operation, in other words, the plugger and drill advance to meet the brush blank and the brush blank is stationary instead of the brush blank advancing to a stationary drill and plugger. The arrangement has the great advantage that the carrier for the brush backs may be made much more rigid and consequently the work performed by the machine is more accurate than is possible where the carrier has a forward and backward movement.

The carrier in my present machine is made in the form of an endless chain

and to which are secured a number of brush holders. In the drawing the carrier contains fifteen brush holders. While the drilling of one brush blank is taking place, the plugger is setting the 70 knots in another brush blank. After each hole has been drilled, the brush blank is moved sidewise and raised or lowered so that it is in position for the next hole to be drilled. At the same time corresponding 75 holes in the other blanks are being tufted. After all of the holes in the brush blank have been drilled or tufted, the carrier which has previously been locked in place, is unlocked and is revolved a sufficient distance to bring the next brush blank into position after which it is again locked in place. The holder in which is located the brush blank which is being tufted is separated from the holder containing the brush 80 blank which is being drilled by another holder. As will be later explained the cams of the positioning mechanism complete two blanks for each revolution of the cams. By arranging the holders on the carrier as described, the same portion of the cam is positioning the carrier during the tufting which positioned the carrier when this brush blank was drilled. In this way, any deviation between the two parts of the cams 95 causes no wrong positioning of the brush blank when it is being tufted.

The positioning mechanism is composed of three groups of elements, one of which moves the carrier horizontally, another of 100 which moves the carrier vertically, and the third of which unlocks the carrier and revolves it after a brush blank has been drilled and a corresponding blank has been tufted. Although the cycle of rotation of the machine covers the making of two three-row brushes, the carrier is unlocked and moved after each brush is completed, that is twice for each cycle of the machine. The carrier and positioning mechanism therefor are 105 supported rigidly upon a frame B made up of convenient pieces suitably secured together. This frame is preferably heavy and strong to insure rigidity of the carrier. The carrier is constructed in the form of an 110 endless chain consisting of fifteen brush blank holders 130 secured together by links 131 pivoted to lugs 132 on the back of the blank holders. The endless chain formed by the blank holders 130 and links 131 revolves upon two sprocket wheels 133 and 134 carried on axles 135 and 136.

The brush blanks C and D are held in place in the holders 130 between a fixed abutment 139 and a movable abutment 140 125 which is yieldingly pressed against the side of the brush blank by the springs 141. The movable abutment 140 is provided with a shoulder 142 adapted to engage the side of the neck of the brush blank, as is plainly 130

seen in Fig. 7. The tip end of the brush blank contacts with a wall 143. The brush blank is inserted in the holder by being pushed in from the left hand side, as seen in Fig. 7, until the tip of the brush blank contacts with the wall 143. The cavity in which the brush blank is received is slightly narrower at the front than at the rear, i. e. the walls are under cut, although the brush blank is not of this shape so that there is a tendency for the brush blank to be crowded back against the rear wall of the cavity and the brush blank is always accurately positioned in the blank holder and held there rigidly.

Two brackets 137 and 138 support the carrier. The front portion of the lower bracket 137 is formed into a grooved guide or shoe 611 upon which the holders 130 are guided when the carrier is shifted. The guide 611 also forms the support for the holders during the drilling and tufting, and the carrier is locked to it during all this time. The holders 130 have projections 612 on their edge which slide in grooves in the said guide 611. The two brackets 137 and 138 which support the carrier are mounted upon a slide 150 which is known as the vertical slide, which is movable in ways 151. These ways are themselves secured to the horizontal slide 152, which is carried in ways 153 in the frame B of the machine. The two slides 150 and 152 are moved by cams 155 and 154 which are respectively the vertical and horizontal cams, said cams being located on a cam shaft 156 mounted in the frame B of the machine. The cam shaft 156 is provided with two toothed wheels 157, which is the feed wheel by means of 158 which is the cam shaft and connected parts are moved, and 159 which is the locking wheel and serves to keep the cam shaft from moving more than a single notch at a time.

The cam shaft 156 is caused to move in the following manner: On the main shaft 35 (see Figs. 1 and 2) which actuates the body of the machine, is located a cam 159, having therein a cam groove 160 in which travels a cam roll 161 on the end of a connecting rod 162 so that a properly timed reciprocation is imparted to the connecting rod by the cam. The connecting rod is guided in a bearing 163 in the frame of the machine and is forked at its rear end for connection by means of a pin 164 to a sliding block 165 which is guided in a slot 166 in a rocking lever 167, which is pivoted at 168. The upper end of the rocking lever 167 is also slotted as shown at 169 to receive the pin 170 which is held in two lugs 171 (one only being visible in Fig. 1) on the bottom of a slide 172 which is known as the bunter slide. The bunter slide is suitably guided in the frame B of the machine and is caused to re-

ciprocate toward and away from the body of the machine by the parts just described. A bunter 173 is secured to the top of the bunter slide and its forward end is in line with one arm of a bell crank 174 (see Fig. 11) pivoted at 175, to the frame B. The other end of the bell crank 174 projects into a slot 176 in the feed dog 177 (see also Fig. 3). The rear end or tail of the feed dog 177 is forked to receive a stud 178 on an upwardly projecting edge of the frame B. The other end of the feed dog is formed into a point 180 for engagement with the teeth of the feed wheel 157, and also has a forward projection 181 for a purpose which will be later described. A spring 182 secured to a post 183 on the rail of the feed dog 177 draws back the feed dog toward the left as seen in Fig. 3 after each reciprocation of the feed dog. One revolution of the main shaft 35 occurs for each hole drilled and each knot of bristles set, and therefore, the bunter slide which is operated from this cam shaft is caused to strike the tail of the bell crank 174 and move the feed dog 177 into engagement with the feed wheel 157 once for each revolution of the main shaft. Thus the feed wheel is moved one notch for each hole drilled and tuft set. Backward rotation of the cam shaft 156 on which the feed wheel 157 is located is prevented by means of a locking wheel 158 and locking pawl 184 mounted on a pin 185 secured to a lug 186 on a little slide 187 which can be moved in ways in the frame of the machine for purposes of adjustment. The tail of the locking pawl 184 is bent at right angles to its general direction and is provided with two inclined surfaces 188 and 189. There is a dog 190 pivoted on a lug 191 on the upper surface of the bunter slide 172 and this dog 190 is also provided with two inclined surfaces 195 and 196 on a portion which is bent toward the tail of the locking pawl 184. The dog 190 is held yieldingly in the position shown in Fig. 1 and Fig. 11 by means of a weight 192 on an arm 193 fastened to a post 194 on the dog. When the bunter 173 moves toward the bell crank 174, the inclined face 195 on the dog 190 contacts with the correspondingly inclined face 188 on the tail of the locking pawl 184, lifting it up so that the point of the locking pawl is out of engagement with the locking wheel 158 and the cam shaft 156 is free to move just at the instant the bunter 173 contacts with the bell crank 174 to move the feed dog 177 and turn the feed wheel 157. On the reverse movement of the bunter, the other inclined surface 196 on the dog 190 contacts with the other inclined surface 189 on the tail of the locking pawl and the dog 190 rides up over the tail of the locking pawl, lifting the weight 192, and then drops down into its normal position. This backward movement

is simply for the purpose of getting the parts into normal position again. A spring 615 under the front end of the locking pawl throws its end up into engagement with the locking wheel as soon as the wheel has been moved.

The foregoing description explains the manner in which the cam shaft 156 upon which is located the vertical cam 155 and the horizontal cam 154 are given their step-by-step rotation in proper time with the movements of the drill and tufter. The horizontal slide 152 is moved in one direction by the horizontal cam 154 by means of a cam roll 200 (see Fig. 3) which is secured to the back side of the horizontal slide 152 and the said slide 152 is moved in the other direction by the spring 201.

The vertical cam 155 gives to the vertical slide 150 its vertical movement through a cam roll 202 secured to a fork 203 (see Fig. 1) which is itself pivoted near the middle of a lever 204. The rear end of the lever 204 is held by means of a vertically adjustable post 205, itself secured to a bracket 206 on the frame of the machine. The adjustment of the post 205 is made by means of an adjusting screw 616 and a set screw 207. The front end of the lever 204 is provided with a hardened roller 208 which forms the point of engagement with the upper end of the slide 150. As the vertical cam 155 revolves, it raises or lowers the lever 204 and thus moves the vertical slide and attached parts in the vertical plane for a predetermined amount.

As previously stated, after the completion of the work of drilling and tufting each brush, it is necessary to unlock the carrier and shift it a sufficient distance so that the next brush blanks will be in proper position to be tufted and drilled, respectively. Each blank holder 130 has drilled in its back side two tapered holes 144, in which are received tapered locking pins 145 which lock rigidly the blank holder and carrier to the guide 611 and hold it so during the drilling and tufting. These pins 145 are secured to a plate 210, which for convenience is called the locking pin plate. This plate is guided upon two bolts 211 which are secured in the rear face of the guide 611 upon which the carrier is supported. Nuts 212 are placed upon the ends of these bolts and a spring 213 is interposed between the nut 212 and the locking pin plate 210. These springs push the locking pin plate 210 and the locking pins 145 forward into the tapered holes in the backs of the blank holders 130. The locking pin plate 210 is slotted as shown at 214, Figs. 7 and 17, and a hook 215 is attached to the locking plate by means of a pin 216. The lower surface of the hook 215 is notched, as shown at 217 and a small roller 218 is secured to the hook

by a stud 219. Under the hook 215, is located a pin 220 the end of which is formed into the shape of a quarter segment (see Fig. 17). This pin is carried on a small cross-head 221 arranged to slide in a slot 222 in a portion of the bracket 137. To this cross-head is pivotally secured one end of a link 223, the other end of which is secured to a lever 224. The lower end of this lever is pivoted at 225 to the bracket 137. The upper end of the lever 224 is attached to mechanism which causes it to be swung about the pivot 225 whenever it is necessary to unlock the blank holders. The small roller 218 on the point of the hook 215 is located so that it will contact with a cam 226 when the locking pin plate has been moved out to a certain point, and as the cam roll 218 rides up on the cam 226 it finally lifts up the hook 215 until the hook is disengaged from the end of the pin 220 on the end of which is formed the quarter segment previously referred to. As soon as the hook is disengaged from the said pin, the springs 213 force the locking pin plate and locking pins back against the back sides of the blank holders, and as soon as the holes 144 in the blank holders come opposite the locking pins 145, the pins snap into the holes and lock the blank holders in place. This mechanism is such that the locking pins are drawn completely out of their holes a sufficiently long time before the hook 215 is disengaged from the pin 220 to permit the blank holders to be moved far enough so that when the locking pins snap back they cannot engage the holes from which they have been withdrawn, but will engage the next holes when the carrier is moved a sufficient distance.

The shifting of the carrier is produced by an arm 230 provided with a pawl 231 held in engagement by a spring 233 with a ratchet wheel 234 fast to the upper sprocket wheel 134. When the arm 230 is moved to the left, as shown at Fig. 6, the ratchet wheel 234, the sprocket wheel 134, and the carrier will be moved with it a distance depending upon the distance which the arm 230 is moved. A slotted link 235 is connected at one end to the arm 230 and at the other end engages a pin 236 on the upper end of the locking pin lever 224. The slot 237 in the link 235 is so proportioned that the locking pin lever 224 is moved a sufficient distance to unlock the blank holders before the pin 236 comes to the end of the slot 237. In Fig. 6 the parts are shown in the position they occupy after the parts have been unlocked and before the shifting of the carrier has begun. Thereafter the further movement begins the shifting of the blank holders and finally disengages the locking pin hook 215 to permit the locking pins to snap back and engage the holes in

the blank holders when the blank holders have been moved into place.

- The locking pin lever 224 is moved by a connecting rod 249 provided with two end members 238 and 239 and a turn buckle 241 for adjusting its length. The end member 239 is pivotally secured to a fork 510 on the upper end of a lever 242 pivoted at 243 to a lug 244 on the frame B of the machine.
- 10 The fork 510 is arranged to swing a little on a stud 511 so that the parts will not bind as the carrier is moved sidewise by the horizontal cam. The lever 242 is itself moved by a hook 246 secured to the lever 242 by a pin 247 sliding in a slot 248 in the lever 242. The hook 246 is guided in suitable ways in a portion 250 of the frame B of the machine. The cam shaft 156 on which the horizontal and vertical cams are 15 located extends rearwardly through the machine and has secured to its rear end a block 251. On this block 251 are two levers 252 and 253, pivoted at 254 and 255 respectively. These levers rotate with the cam shaft 156 and after every 180 degrees of rotation the 20 end of one of the levers 252 and 253 comes under the hook 246, as seen in Fig. 1. Both of these levers 252 and 253 are cut away as shown at a b, to permit this arm of the 25 lever to rotate without striking the projecting end of the hook 246. On the long arms of the levers 252, 253 are formed flat spaces c c suitable for engagement with the corresponding flat space on the dog 256. This 30 dog is pivoted at 257 to the rear end of the bunter slide 172, which reciprocates every time a hole is drilled and a tuft of bristles set. This pawl 257 is held up into the position shown in Fig. 1 by means of a flat spring 258. When one of the levers 252 and 35 253 has revolved to such a position that it is in the path of the dog 256, the next rearward movement of the bunter slide 172 carries the dog 256 under the lever 252 or 253, as the case may be, the dog 256 being depressed against the action of the spring 258. At the end of the stroke of the bunter 40 slide the dog 256 snaps up and on the forward movement of the bunter slide engages the flat surface c and swings the lever about its pivot 254 or 255. At this time the upper end of the lever is in engagement with the hook 246, the forward movement of the bunter slide carries the lower end of the lever 252 or 253 toward the right and pulls the locking pin lever 224 and the carrier moving arm 230 over to the left to unlock the blank holders and rotate the carrier. At the 45 end of the forward movement of the bunter slide at which time the feed wheel and cam shaft are rotated one notch, the lever 252 or 253 as the case may be, being rotated by the cam shaft is disengaged from the dog 256, while the bunter slide is still in its 50 forward position. As soon as the lever 252,

or 253, is released, the spring 512 restores the parts to normal position which is that shown in Fig. 1. The levers 252 or 253 are restored to the position shown in Fig. 1 by springs 618 and 619, one end of which is fastened to a stud 620 on the cam shaft. The lever then rests against a pin 621 so that it is ready to be engaged on the next rotation of the cam shaft.

For a reason later to be explained, it is necessary to turn the cam shaft 156 one extra notch of the feed wheel 157 at the end of each cycle of movement of the machine. This is accomplished by means of a tail piece 260 secured at the rear end of the cam shaft 156. Once in each revolution this piece 260 comes to a position in the way of an inclined surface 261 on the rear end of the bunter slide 172. When the bunter slide comes back at the end of the stroke, the cam surface 261 strikes the tail piece and pushes it to one side to the position shown in Fig. 4, causing the cam shaft 156 to rotate a distance of one notch of the feed wheel. To permit this rotation the locking wheel 158 has one tooth removed as seen at 513, in Fig. 11, so that at this time the locking pawl 184 does not interfere with the movement of the feed wheel and connected parts.

The machine is controlled by the operator by means of a pedal 270 see Fig. 2 connected to a lever 271 which is itself connected to one arm of the bell crank 272. The other arm of this bell crank 272 engages a fork 273 secured to the upper end of a clutch lever 274 which operates the clutch 275. When the operator presses down the treadle the clutch engages the fly wheel 276 and the machine starts. As it is necessary to move the cam shaft by hand sometimes there is provided a hand lever 514 (see Figs. 3 and 11) pivoted to an adjustable block 515 movable by screws 516 in a slot 517 in the frame of the machine. The other end of the lever 514 is provided with a hook shaped pawl 518 which engages the feed wheel 157 and prevents its rotating backward after it has been moved forward by the feed dog 177. The projection 181 on the feed dog 177 extends under the hook shaped pawl 518 which forms a part of the lever 514 so that when the lever 514 is lifted up by hand the feed dog 177 and the pawl 518 are both disengaged from the feed wheel and the feed wheel is then free to be moved by hand. The spring 519 keeps the hook pawl 518 normally in engagement with the feed wheel.

The operation of the machine is in general as follows: The operator inserts an un-drilled brush blank C in the proper blank holder 130 and a drilled blank D in the blank holder next but one above. In practice, and after the machine has been started,

there are blanks in all the holders 130, and the workman removes the tufted brush blank from one of the top holders and inserts the undrilled blanks at this point. He then presses the treadle, and the drill begins at point *f* in Fig. 18 to drill the holes. At the same time, the tufter begins to fill the holes starting at the corresponding point in the already drilled brush blank. At each revolution of the main shaft 35 the drill bores a hole, the knot picker selects a knot of bristles, the die cuts a staple and the plunger sets the knot of bristles in the hole by means of the pusher. After the drill has been drawn out of the drilled hole, the feed wheel 157 is moved one notch by means of the bunter and intermediate parts. The movement of the feed wheel moves the carrier to the left (see Fig. 3) the distance of one notch and the vertical cam lowers the carrier a slight amount because as will be seen from Fig. 18 the rows of bristles in the finished brush are not parallel but converge toward the tip of the brush. This general movement of the parts continues until the end of the first row of brush No. 1 is reached. After the last hole of this row has been drilled, the next movement of the feed wheel lowers the carrier to position the brush blank to begin the second row of holes. As the second row of holes is horizontal, that is follows the median line of the brush, the brush is not moved vertically while the second row is being drilled and tufted. At the end of the second row the carrier is lowered by the vertical cam, and the drilling of the third row begins. While this row is being drilled and tufted the carrier is raised slightly after each hole has been drilled. The last hole in the third row is marked *g* in Fig. 18. After this hole has been drilled and tufted, one of the levers 252 and 253 has come in contact with the dog 256 on the rear end of the bunter slide which results in unlocking the carrier and shifting it to bring the next pair of blanks in position to be operated upon. The same forward movement of the bunter slide which unlocks the carrier and shifts it, moves the feed wheel one notch and the corresponding movement of the vertical cam raises the brush blank so that it is in position to have the hole *h* in brush blank No. 2 drilled and the corresponding hole in the brush blank which is before the plunger tufted. The drilling and tufting of this pair of brush blanks is the same as that previously described, except that the path followed by the drill and plunger is different from that followed by the drill and tufter during the drilling and filling of the first pair of brush blanks. The paths of movement of the two brush blanks will readily be seen from an examination of Fig. 18. The starting point for the first and second brushes being in-

dicated respectively at *f* and *h* and the finishing point being indicated by *g* and *k* respectively. It will be seen that the next point after the hole marked *k* in Fig. 18 will be the hole *f* which is the starting point 70 of the first brush and that there is a considerable vertical distance between these two holes. The carrier is lifter through this vertical distance by means of the vertical cam but as this distance is so large that it 75 would make the cam too steep if the movement were made during a single notch of the feed wheel, an additional notch is provided in the feed wheel, as has been previously described. The feed wheel therefore 80 has eighty-one notches, forty for the forty tufts of bristles in the first brush, forty for the second brush and one additional hole at the end of each cycle of revolution to assist in setting the machine back to its starting point. The feed wheel is moved this additional notch by the tail piece 260, as previously described. The machine is then ready to begin a second cycle of movements.

In Fig. 19 there is shown a diagram of 90 the vertical and horizontal cams and there has been indicated on the cams the various points of the cams which are in contact with the cam roll at the time when the holes at the beginning and end of each brush are 95 being drilled. For convenience the same reference characters have been applied to this figure as are applied to Fig. 18 to indicate corresponding positions on the cam. It will be noticed that the starting points on 100 the two cams are at a distance of about ninety degrees from each other owing to the fact that the cam roll for the vertical cam is above the cam while the cam roll for the horizontal cam is at the left hand side 105 of the cam.

What I claim is:—

1. The improved machine for drilling and filling a brush having an odd number of rows which comprises a drill and tufter, and a carrier holding a plurality of brush blanks, positioning mechanism for said carrier making a complete cycle of movement during the completion of the work upon two brush blanks, and shifting mechanism shifting the carrier twice for each cycle of movement of the positioning mechanism. 110 115

2. In a machine of the character described, the combination of a tool to operate upon a brush blank, a carrier holding a plurality of brush blanks, a shaft, two cams thereon moving the carrier in two directions in a plane at right angles to the tool, said cams by a single rotation of the cam shaft controlling the positioning movements of the carrier during the operation on two successive blanks, and shifting mechanism shifting the carrier to present the next blank to the tool, said shifting mechanism acting twice during each revolution of the cam shaft. 120

3. The improved brush machine which comprises a drill and tufter, a carrier holding a plurality of brush blanks, a shaft, two cams thereon moving the carrier in two directions in a plane at right angles to the drill and tufter, said cams controlling the positioning movements of the carrier during the operation on two successive pairs of brushes during one revolution of the cam shaft, and shifting mechanism shifting the carrier to present a new pair of brushes to the drill and plugger respectively, said shifting mechanism acting twice during each revolution of the cam shaft.
4. In a brush making machine, the combination of a drill and plugger, a carrier composed of a series of work holders, automatic positioning mechanism therefor moving the said carrier in two directions in a plane at right angles to the said drill and plugger, a cam shaft, cams thereon acting on the said carrier to position the same in said plane, a feed wheel on the said cam shaft, a reciprocating member moving the said wheel step by step, a lever on the cam shaft and in the path of the said reciprocating member once for each revolution of the cam shaft, shifting means to move the holders comprising the carrier bodily and connections from the said lever to the said shifting means so that the said reciprocating member will actuate the said lever to shift the carrier once for each revolution of the cam shaft.
5. In a brush making machine, the combination of a drill and plugger, a carrier composed of a series of work holders, automatic positioning mechanism therefor moving the said carrier in two directions in a plane at right angles to the said drill and plugger, a cam shaft, cams thereon acting on the said carrier to position the same in said plane, a feed wheel on the said cam shaft, a reciprocating member moving the said feed wheel step by step, two levers pivoted on the cam shaft at substantially 180 degrees from each other, each lever coming into the path of said reciprocating member once for each revolution of the cam shaft, shifting means to move the holders comprising the carrier bodily, and connections from the said levers to the said shifting means so that the said reciprocating member will actuate the said levers to shift the carrier twice for each revolution of the cam shaft.
6. In a machine of the character described, the combination with a plugger having a channel therein and a plugger tongue working in the said channel of a bristle reservoir, a knot picker consisting of a reciprocating member having a notch in one side thereof, said knot picker entering the reservoir, parallel and adjacent to a wall thereof, a grooved guide for said knot picker substantially at right angles to the bristle channel in the said plugger, a cam to actuate said knot picker, said cam having a rest therein so that said knot picker will stand still for a portion of its stroke with the said notch therein at the junction of the picker and plugger channels.
7. In a machine of the character described, a plugger slide therefor movable in ways toward and away from the work, a pusher sliding in a channel in the said plugger, a reciprocating member actuating the said pusher, cushion pins on the said plugger slide in the path of the said moving member whereby the plugger slide stands still during the first part of the movement of the pusher is then moved forward when the moving member contacts with the said spring pins and then stands still during the further advance of the plugger.
8. In a machine of the character described, the combination with a plugger slide having a slot therein, a pusher movable relatively to the plugger slide in the same direction, an actuating member moving the pusher, said member projecting into the slot in the said plugger slide so that the plugger slide is moved by the said member in unison with the pusher for a portion of the stroke near the ends thereof.
9. In a machine of the character described, a plugger slide therefor movable in ways toward and away from the work, a stop arm on the said plugger slide, a stop on a fixed part of the machine contacting with the said stop arm, a pusher sliding in a channel in the said plugger, a reciprocating member actuating the said pusher, cushion pins on the said plugger slide in the path of the said moving member whereby the plugger slide stands still during the first part of the movement of the pusher is then moved forward when the moving member contacts with the said spring pins and until the stop arm contacts with the said stops and then stands still during the further advance of the pusher.

In testimony whereof I affix my signature, in presence of two witnesses.

HERMAN M. SCHWARTZ.
